DES. 2184

Robert Hoe, Jr. of New York, N.Y.

Letters Patent No. 2184 - Dated Oct. 10, 1865.

Design for a Copying Press

The schedule referred to in the Letters Patent and making part of the same,
shall whom it may concern,

Bent knows that Robert Hoe, Jr. of the
City, County and State of New York, have invented a new and original
design for Copying Press, and I, therefore, declare that the following
is a full, clear and exact description thereof, which will enable
others skilled in the art to make and use the same, reference
being had to the accompanying drawing, forming part of this
specification.

The drawing is a perspective view of a copying press
showing my design.

This invention relates to a new and original design for
a copying press in which it is intended to combine simplicity with
strength.

A represents the base of the press which is of rectangular
form having an open eye or head a around its upper edge and
a unicircular projection b at the center of each end with lugs c
through which screws d will pass to secure the press to any fixture.
The projections b have the ends e extending around their upper

edges and below the head a have a rounded portion d.

The platen B of the press is also of rect-angular form having a pyramidal upper surface e, as shown clearly in the drawing, the socket C of the screw D being of cylindrical form and having a square base f. F. H. are the pillars which support the cross bar E. These pillars are of cylindrical form and of equal diameter throughout their entire height.

The cross bar F is of curved form and is shown in the drawing the screw D which passes through its center being provided with a handle G, which gradually increases in diameter or thickness from its central part g, through which the screw passes to the outer ends, the parts h, h, of the handle which are grasped by the hands being of circular form in their transverse section.

Claims in view and device is secure by letter patent.

The form or configuration of the parts herein shown and described to form a new and original design for a copying press.
